his Attorney

UNITED STATES PATENT OFFICE.

MICHAEL McCANN, OF GLENMORRIS, NEW YORK, ASSIGNOR TO FREDERICK OSANN COMPANY, OF NEW YORK, N. Y., A CORPORATION OF NEW YORK.

SEWING MACHINE.

Application filed May 16, 1925. Serial No. 30,753.

My invention relates to sewing machines adapted to make zig zag stitches and of the general character of the machine described in my former Patent 1,461,428, of July 10, 1923. In the machine of my said former patent the needle guide and loopers are provided with mechanism, by means of which they can be shifted to form zig zag stitches of varying length, or held in the position 10 in which they will form a series of straight stitches, the mechanism, generally speaking, consisting of a vibrating block provided with a pin adjustable in the vibratory center of the block to more distant position, 15 through which pin, when shifted from the vibratory center of the block, the desired vibratory movement is given to the mechanism which in turn vibrates the needle guide and the loopers. In the mechanism of my 20 former patent the position of the pin in the vibrating link is controlled by a cam formed so that during a portion of the sewing of a button hole the pin is held concentric with the pivot of the block. During 25 another portion of the sewing of the button hole the pin is shifted to a position where it gives the needles and loopers the vibratory movements needed for the sewing of the zig zag stitches of the sides of the button hole, 30 and during other portions of the sewing of the button hole the pin is shifted to a position where it gives to the needles and the loopers the vibratory motion needed for the forming of barring stitches at the 35 ends of the button hole. The object of my present invention is to relieve the pin actuating cam of my former machine from the duty of shifting the pin to the barring stitch position and to effect this positioning of 40 the pin by means of a separate and independent cam preferably made adjustable so as to vary the periods during which the machine shall operate in making barring stitches, and my invention consists in the 45 new combination of mechanism by means of which the desired movements are given to the adjustable pin sliding in the vibrating block.

The nature of my improvements will be best understood as described in connection with the drawings which illustrate portions of the machine of my former patent provided with the new improvement in the

mechanism for actuating the adjustable pin, and in which—

Figure 1 is a horizontal sectional plan generally similar to the right hand portion of Figure 2 of my former Patent 1,461,428, but showing in addition the adjustable cam which constitutes an important feature of my present invention.

Figure 2 is a sectional elevation taken as on the line 2—2 of Fig. 1, and generally similar to Figure 7 of my former patent with a modification in the form of the cam for actuating the pin in the vibrating block.

Figure 3 is a sectional elevation taken as on the line 3—3 of Fig. 1, which view is generally similar to Fig. 7 of my former patent but shows the new adjustable cam and its connections with the mechanism for actuating the pin in the vibrating block.

Figure 4 is an elevation generally similar to that shown in Fig. 3 of my former patent so far as the parts illustrated are concerned.

Figure 5 is a side elevation of my new adjustable cam.

Figure 6, an edge view of this cam.

Figure 7, a side elevation showing the two cam disks adjusted to non-operative position, and

Figure 8 is a view of a button hole such as my machine is adapted to make.

While, as I have before stated, my present invention is partly an improvement on the mechanism shown in my former Patent 1,461,428, in some details of the illustrated mechanism I have varied the modification of the said patented machine shown in my other prior Patent 1,483,185 of February 12, 1924, and, so far as the illustrated parts of my improved machine are the same as those of the last mentioned patent, I have used the index letters applied to the same parts in my said patent of February 12, 1924.

A indicates the bottom casing of the machine. A' the upright arm of the casing. A² a portion of the horizontally extending portion of the casing and A³ the casing housing the needle guides and other operative parts of the machine. B is the removable bottom plate of the machine. D is the main driving shaft of the machine. D' is a hub extension of casing A to provide a sufficient bearing for shaft D. D² is a stop disk hav-

2

ing the stop recess D^4 , D^5 and D^6 , fast and loose pulleys on the shaft D , and D^7 an eccentric secured on this shaft, and D^8 , a gear wheel secured to the shaft D , all as in my 5 said former machine. E is an eccentric rod actuated by the eccentric D^7 and connected by lever arms E' with the rock shaft E^2 which, through a lever arm E^3 , actuates the needle bar E^4 , to the end of which the needles 10 E^5 are secured. F is a gear wheel engaged by the gear D^8 and secured to a shaft F' to which is also secured a cam F^2 which engages the forked end F^4 of the vibrating block, more fully described in my Patent 15 1,461,428, and here indicated by the symbol F^5 . G is a rock shaft carrying at its front end the needle guide G^2 and at its rear end the actuating lever G^3 which is slotted, as indicated at G^5 , and has a curved end G^4 20 which is pivotally connected with a lever arm H , extending out from the rock shaft H' which shaft, as described in my former patents, imparts a vibratory movement to the loopers. 25 I is a shaft to which an intermittent rotary movement is given by mechanism described in my former patents. To this shaft are secured a cam indicated at I^5 , the function of which is described in my former 30 patents, a cam indicated at I^6 which is generally similar to the cam as illustrated in my Patent 1,483,185, except that it has but two operative sections, one here indicated at i which corresponds to the position when a 35 zig zag motion is given to the needles and loopers for stitching of the sides of the button hole, and another portion, here indicated at i' , which corresponds to the position given to the needles and loopers when padding stitches are being formed. In my 40 present construction I provide a new cam section on the shaft I , as shown at T , T' , Figure 1, and in detail in Figures 5, 6, and 7. This cam is made up of two concentric 45 disks T and T' , the one secured to and the other rotatable on the shaft I . From the disk T' extends a pin T^2 which passes through a segmental slot T^3 in the disk T and by means of which, and a nut, the two 50 disks can be clamped together in any position that the slot permits them to take. The two disks are similar in conformation, having long and short circular portions indicated at T^4 and T^5 , between which occurs 55 the two depressed portions indicated at T^6 , T^7 .

K is a lever pivoted at K' provided with a cam roller K^2 which engages in the cam I^6 and K^3 is a rod connected with the free end 60 of the lever K and adjustably connected at its upper end with the slot K^6 of the lever arm K^4 which carries on its free end the pin K^7 moving in the slot in the block F^5 and extending into the slot G^5 of the lever G^3 . 65 K^5 is a pivot on which the arm K^4 moves,

which pivot, in the machine described in my former patents, was not adjustable but in my present machine is made adjustable by being attached to a supporting link U^2 and connected at one end of lever U the other end 70 of which is pivoted at K' . U^2 is a spring acting to press the lever U downward and U' is a cam roller attached to the end of the lever U and resting on the cams T , T' , against which it is pressed by the action of 75 the spring U^3 .

L is a rock shaft actuated as described in my former patents and connected to actuate the knife holding bar L^2 holding the knife 80 L^3 at its end.

M is the longitudinally movable stop shaft having the buffer stops M^4 and M^5 , as described in my Patent 1,483,185, and carrying the arm M' to which is secured the stop finger M^2 which operates in connection with the disk D^2 , as described in my said patent. M^3 is a belt shifting arm attached to the shaft M by which the belt m^3 is shifted between the fast and loose pulleys D^5 and D^6 . 90 Pivoted secured on the shaft M is an arm N carrying the pin N' and having an extension N^2 , all as described in my said former patent. O is a pivot carrying the locking hook O' which is normally pressed to engage the pin N' by the spring O^2 . N^4 , as in my former patent, is a support for the spring N^5 which acts to press the arm N upward.

The operation of the described parts of my machine is precisely the same as described in my Patent 1,483,185, except that the cam I^6 has in my present machine only the duty of shifting the pin K' from a point where it coincides with the pivot of the vibrating block F^5 to a point at the proper distance from said pivot for the making of the zig zag stitches formed in the sides of the button hole. Thus, so long as the cam roller K^2 on the link K is in contact with the cam surface i , the zig zag stitches at W^4 100 in Fig. 8, will be formed. The duty of shifting the pin K' to a position in which the needles and loopers will be vibrated to form the barring stitches indicated at W^3 and W^5 in Fig. 8, is, in my present machine, imposed on the cams T , T' , which, at properly timed intervals with regard to the sewing of the button hole, permit the spring U^3 to 105 move the lever U and the connected pivot supporting link U^2 downward so as to depress the pivot K^5 , turning the arm K^4 on its pivotal connection with the link K^3 as a fulcrum and shifting the pin K' in the vibrating block to a point more distant from its vibrating center.

The number of bar stitches to be taken at the ends of the button hole is determined by 110

the relative adjustment of the cam disks T, T', which, when adjusted as shown in Figure 7, are not operative as cams. In this adjustment there will be no barring stitches formed while, as adjusted in Fig. 5, it will be seen that the barring stitches will be formed.

The button hole, as illustrated in Fig. 8, has first formed the row of padding stitches indicated at W². On the completion of these stitches the cam I⁶ is turned to a point where the cam roller will rest on the cam surface *i*, shifting the pin K⁷ from the vibrating center of the block F⁵ and, at the same time, the cam roller U' is permitted to move down into one of the depressions T⁶ of the cams T, T', thus, by the mechanism described, shifting the pin K⁷ still further away from the vibrating center of the block F⁵ so that the group of barring stitches indicated at W³ in Figure 8 is formed. As the cam made up of the disks T, T', revolves to a point where the cam roller U' is raised on to the surface T⁴, the pin K⁷ is shifted back to the position determined by the cam I⁶ and the rows of zig zag stitches indicated at W⁴ are formed and as these stitches reach the end of the button hole the cam roller U' passes into a recess T⁶ of the cam disks T, T', again shifting the pin K⁷ to a point more distant from the vibrating center of the block F⁵, so that the barring stitches indicated at W⁵ are formed, after which the machine is automatically stopped.

Having now described my invention, what I claim as new and desire to secure by Letters Patent, is:—

1. In a sewing machine adapted to form zig zag stitches having a vibratory guide for the needles and a vibratory device for shifting the loopers and means for operating said vibratory mechanism including a pivoted cam actuated vibratory block and a pin movable in said block to and from its pivotal center by means of which, when it is moved from said center, vibratory motion of greater or less extent is given to the needle guide and looper shifting mechanism, the combination therewith of means including an actuating cam for shifting the pin to and from the pivotal center of the vibrating block and means including a separate actuating cam for shifting the pin to a point in the vibrating block more distant from its pivotal center.

2. In a sewing machine adapted to form zig zag stitches having a vibratory guide for the needles and a vibratory device for shifting the loopers and means for operating said vibratory mechanism including a pivoted cam actuated vibratory block and a pin movable in said block to and from its pivotal center by means of which, when it is moved from said center, vibratory motion of greater or less extent is given to the needle guide

and looper shifting mechanism, the combination therewith of means including an actuating cam for shifting the pin to and from the pivotal center of the vibrating block and means including a separate actuating cam, ⁷⁰ adjustable as to its period of operation, for shifting the pin to a point in the vibratory block more distant from its pivotal center.

3. In a sewing machine adapted to form zig zag stitches having a vibratory guide for the needles and a vibratory device for shifting the loopers and means for operating said vibratory mechanism including a pivoted cam actuated vibratory block and a pin movable in said block to and from its pivotal center by means of which, when it is moved from said center, vibratory motion of greater or less extent is given to the needle guide and looper shifting mechanism, the combination therewith of means for shifting the pin in the vibrating block comprising a pin supporting arm, an adjustable pivot for said arm, means pivotally connected to an intermediate portion of said arm to actuate it to move the pivot from the pivotal center of the vibrating block including an actuating cam, and means for independently shifting said pin in the block including an independent cam connected to shift the pivotal support of the arm and thereby turn ⁹⁵ the pin carrying arm on its intermediate pivotal connection.

4. In a sewing machine adapted to form zig zag stitches having a vibratory guide for the needles and a vibratory device for shifting the loopers and means for operating said vibratory mechanism including a pivoted cam actuated vibratory block and a pin movable in said block to and from its pivotal center by means of which, when it is moved from said center, vibratory motion of greater or less extent is given to the needle guide and looper shifting mechanism, the combination therewith of means for shifting the pin in the vibrating block comprising a pin supporting arm, an adjustable pivot for said arm, means pivotally connected to an intermediate portion of said arm to actuate it to move the pivot from the pivotal center of the vibrating block including an actuating cam, and means for independently shifting said pin in the block including an independent cam, adjustable as to its period of operation, connected to shift the pivotal support of the arm and thereby turn the pin carrying arm on its intermediate pivotal connection.

5. In a sewing machine having the features of claim 2, the construction of the adjustable cam made up of two concentric and relatively rotatable cam faced disks by adjusting which the periods of dwell of the pin in its more distant position in the vibratory block can be varied in duration.

MICHAEL McCANN.
